SUPPORT FOR AXMINSTER TUBE FRAME

Walter Y. Robb, Whitinsville, Mass., assignor to Crompton & Knowles Loom Works, Worcester, Mass., a corporation of Massachusetts

Application December 8, 1954, Serial No. 473,963

6 Claims. (Cl. 139—10)

This invention relates to improvements in Axminster looms and it is the general object of the invention to provide a simple form of support for tube frames to prevent them from moving angularly with respect to the links of the transporting chain which support them.

An Axminster loom employs a large number of tube frames detachably connected to transporting chains which are trained around pullover and overhead sprocket wheels forming part of the structure which supports the tube frames. In the past it has been customary to connect the tube frames to double links in the transporting chains in such a manner that a tube frame passing from one side to the other side of a sprocket wheel has considerable motion with respect to the chains. This undesirable motion subjects the tube frame supporting hooks to considerable strain which results occasionally in their breakage with resultant dropping of the tube frames from the chains.

It is an important object of the present invention to provide each of certain links of at least one of the transporting chains with a pair of supporting arms for the associated tube frame, these arms being connected to their chain links in such manner as to maintain a substantially fixed angular position of the tube frame with respect to its link to prevent the previously mentioned undesirable motion of the tube frame with respect to the chain.

The transporting chains have double links alternating with single links, the double links comprising a pair of links spaced transversely of the length of the chain and so related to the tube frame that a tongue rigid with a bracket on the end of the tube frame passes between the two links and a supporting hook on the tube frame passes over one of the two links. It is a further object of the invention to provide tube frame support means associated with the double links so constructed as to move around the sprocket wheels of the loom with the double links and remain in engagement with the tube frame to prevent the aforesaid objectionable movement of the tube frame.

The supporting hooks at the ends of the tube frame are detached from the transporting chains by a rocking or pivotal movement caused by clutches which move inwardly against the hooks preparatory to a tuft forming operation of the loom. It is a further object of the invention to have the supporting arms which engage the bar of the tube frame so positioned as to permit the usual rocking movement of the associated hook. This result is accomplished as set forth herein by having the hook between the supporting arms and having the latter spaced sufficiently from each other to enable the hook to rock around its pivot on the tube frame.

The preferred form of the invention is so constructed that it can be applied to existing transporting chains by a slight change in the latter. In a modified form of the invention the support arms are integral with one of the links forming the double link.

In order that the invention may be clearly understood reference is made to the accompanying drawings which

2

illustrate by way of example two embodiments of the invention and in which:

Fig. 1 is a vertical section through a pullover shaft of an Axminster loom showing a short section of transporting chain and associated tube frames and having the preferred form of tube frame support applied thereto,

Fig. 2 is an elevation looking in the direction of arrow 2, Fig. 1, partly in section, showing a tube frame supported by a transporting chain and a clutch to disengage 10 the hook from the chain,

Fig. 3 is a vertical section on line 3—3, Fig. 2,

Fig. 4 is a horizontal section on line 4—4, Fig. 3,

Fig. 5 is a detailed view similar to a part of Fig. 2 but showing the clutch moved to hook releasing position 15 and showing the manner in which the clutch is modified to accommodate the supporting arms on the chain,

Fig. 6 is an elevation of a modified form of the chain wherein the supporting arms are integral with a chain link, 20 Fig. 7 is a side view looking in the direction of arrow 7,

Fig. 6, and

Fig. 8 is a plan view looking in the direction of arrow 8, Fig. 6, showing the relation between the supporting arms of the modified form and the transporting chain.

Referring to Fig. 1, the pullover shaft 1 of the loom 25 has secured thereto a pullover sprocket wheel 2 which drives a transporting chain 3. This chain has double links alternating with single links, the double links as shown in Fig. 4 comprising link members 5 and 6 which are spaced transversely of the length of the chain and the single links being indicated at 7. Pivot pins 8 connect the double and single links and in the preferred form of the invention perform an additional function which will be described hereinafter.

The tube frame 10 comprises an elongated bar 11 from 35 which extend a plurality of yarn tubes 12 for the tuft yarns Y, see Fig. 1. Secured to the end of bar 11 is a bracket 13 having an inside spool bearing part 14 to support the yarn spool or beam B and having an outside part 15 which extends upwardly from the bar, is then bent 40 outwardly away from the bearing part 14, and then extends upwardly to form a tongue 16 which extends between links 5 and 6. Pivot to the bracket 13 is a supporting hook 17 which is normally urged in a direction away from the spool bearing 14 by a spring 18 which, 45 however, permits the hook to be moved toward the spool bearing. A clutch C has side cheeks 20 and 21 which engage opposite vertical sides of the bar 10 and has a foot 22 to pass under the bar. The clutch also has a stud 23 for engagement with the hook 17.

In normal operation the pullover shaft 1 turns intermittently to move the tube frames one at a time to a releasing station T directly under the shaft. When a tube frame is in the releasing station and is to be released from the chain the clutch C is moved to the left, Fig. 2, 55 so that the stud 23 engages hook 17 to rock the latter toward the spool support 14 until the hook is out of vertical alignment with the link 6. As the clutch moves to releasing position the foot 22 effects a slight rising motion of the tube frame to take the weight of the tube frame 60 off the hook and permit the latter to move freely to releasing position. With the tube frame thus released from the chain the clutch then moves downwardly to permit the tube frame to have its usual tuft forming operation, after which the clutch is again raised to cause entry of the tongue between the double links, after which the clutch is moved away from the tube frame to enable the hook to again extend over the link 6 to connect the tube frame to the chain. It is to be understood that the parts shown in Fig. 2 are duplicated on the opposite side of 65 the loom.

The matter thus far described except as noted herein-after is of common construction and operates in the usual

manner. For further description of the tube frame reference may be had to Patent 2,161,761. The invention, however, is not limited to the specific type of tube frame shown in that patent.

It will be understood that in Axminster looms as previously made the tube frame which is to the right of the releasing station, Fig. 1, will sag to a position which is nonradial with respect to shaft 1 due to the looseness between the tongue and the space between adjacent ends of the single links 7. A tube frame on the left of position T will also sag but in a direction opposite with respect to the chain to the sagging of the tube frame to the right of position T. A tube frame passing from the right of position T to the left thereof will have considerable motion relative to the chain due to the looseness in the connection between the tube frame and the chain. This same motion also exists with respect to any sprockets in the overhead construction around which the chain 3 is trained, and causes considerable wear which occasionally results in breakage of the hooks and dropping of a tube frame from one or the other of the transporting chains.

In carrying the preferred form of the invention into effect each of the double links is provided with a supporting member designated generally at S. Each member S includes two substantially parallel arms 30 and 31 connected integrally at their upper ends by an arch 32. As shown in Fig. 2 the arch 32 is located between the yarn spool and the sprocket 2 but the invention is not necessarily limited to this particular location of the arch. The member S has hubs 33 and 34 through which pass the pivot pins 8. These pins are somewhat longer than those found in the ordinary transporting chain and serve to hold the member S and therefore the arms 30 and 31 in fixed angular position with respect to the links 5 and 6.

The arms 30 and 31 define between them a space 35 into which the bar 10 extends when the tube frame is on the transporting chains. The outer ends of the arms 30 and 31 are spaced a distance substantially equal to the width of the bar 10, as is apparent in Fig. 1, and hold the tube frame against angular motion with respect to its double link. When the latter engages a sprocket wheel the tube frame is disposed substantially radially with respect to the axis of the sprocket, as shown in Fig. 1. This is a desirable but not necessary condition. The lower inner ends of the supporting arms may be rounded as at 36 to facilitate entry of the bar 10 into the space 35 when a tube frame is being returned to the chain after a tuft forming operation.

The arms 30 and 31 are on opposite sides of the hook 17 and the cheeks 20 and 21 of clutch C are cut away as at 37 to provide clearance for the ends of the supporting arms, as suggested in Figs. 2 and 5. The arms 30 and 31 are so located that they do not interfere in any way with the motion of the clutch C to hook releasing position, or the usual movements of hook 17 with respect to link 6.

In the modified form of the invention shown in Figs. 6 to 8 one of the links of the double link is made integral with tube frame supporting arms. Thus, a link 40 corresponding to link 6 is integral with arms 41 and 42 corresponding to arms 30 and 31 respectively defining between them a space 43 corresponding to space 35. Parts 40, 41 and 42 together form a support unit or member 45 made preferably although not necessarily with hubs 46 through which pass pins 47. As shown in Fig. 8 link 5 and the single links 7 are the same as in the preferred form and the unit 45 replaces the link 6. The hook 17

will extend over the link 40 when the modified form of the invention is used and the arms 41 and 42 act in the same manner to support tube frame as already described for the preferred form.

The preferred form of the invention can be added to the usual transporting chain merely by employing pins 8 of a length greater than that ordinarily found in transporting chains, while the modified form of the invention can be utilized where new chains are built to incorporate the invention. Although it is contemplated that both chains in a wide Axminster loom will be made with the supporting arms, it will be sufficient on narrow looms if only one of the chains is equipped with the supporting arms.

From the foregoing it will be seen that the invention sets forth simple means for supporting tube frames in such manner as to prevent their angular motion with respect to the double links of the transporting chains. The invention contemplates a pair of arms, as 30 and 31 in the preferred form or 41 and 42 in the modified form, which are held against angular motion with respect to the double link and extend on opposite sides of the bar 10 to engage the latter at points spaced from the double link. The hook 17 is between the supporting arms and is free to act without interference by them. In the preferred form the invention can be applied to existing transporting chains merely by altering the latter to the extent of lengthening the pivot pins 8, whereas in the modified form the unit 45 has the arms integral with one of the double links.

Having now particularly described and ascertained the nature of the invention and in what manner the same is to be performed, what is claimed is:

1. In an Axminster loom operating with a tube frame comprising a longitudinal bar having secured to an end thereof a bracket formed with a tongue and having pivoted thereto a supporting hook, a transporting chain for the tube frame including a pair of links spaced from each other transversely of the chain between which said tongue extends and over one of which said hook extends, and two spaced support means on the chain fixed with respect to each other and in fixed angular position with respect to the link over which the hook extends engaging the tube frame on opposite sides of the hook to prevent angular movement of the tube frame relative to said link.
2. The structure set forth in claim 1 wherein said support means includes arms which engage opposite sides of said longitudinal bar.
3. The structure set forth in claim 2 wherein said arms are integral with one of said links.
4. The structure set forth in claim 2 wherein said arms are integral with the link over which said hook extends.
5. The structure set forth in claim 2 wherein said links are pivoted at their ends to pins spaced longitudinally along the chain and said support arms are supported by said pins.
6. The structure set forth in claim 2 wherein the tube frame supports a yarn spool and the chain is trained around a pullover sprocket wheel and said support arms are integral with an arch which is between the spool and sprocket wheel when the pair of links are operatively engaged with the sprocket wheel.
